INVENTOR

Walter Thompson

UNITED STATES PATENT OFFICE.

WALTER THOMPSON, OF NEWARK, NEW JERSEY.

MUFFLING ATTACHMENT FOR VIOLINS.

SPECIFICATION forming part of Letters Patent No. 417,292, dated December 17, 1889.

Application filed August 8, 1889. Serial No. 320,160. (No model.)

To all whom it may concern:

Be it known that I, WALTER THOMPSON, a subject of the Queen of Great Britain, residing in Newark, county of Essex, and State of New Jersey, have invented certain new and useful Improvements in Muffling Attachments for Violins, of which the following is a specification.

This invention relates to an improved muffling attachment to violins and similar stringed instruments by which the muffling of the sounds of the instrument is effected in an easy and effective manner by the chin of the player, so as to dispense with a separate mute, which has to be placed in position on the bridge of the instrument whenever it is desired to damp the sounds of the strings. This putting in position of the mute is always connected with a certain loss of time and inconvenience to the player, as it requires the manipulating of the mute both in putting it on and in removing it from the bridge.

The object of this invention is to overcome the objections to the mute heretofore in use and to supply a conveniently-operated muffling attachment to violins and similar instruments by which the sounds can be muffled without interrupting the playing of the instrument and without causing the slightest inconvenience to the player; and the invention consists of a muffling attachment to violins and other stringed instruments composed of muffling-plates, arranged at opposite sides of the bridge, which plates are connected by pivot-rods with a muffling-lever that is fulcrumed to the under side of the tail-piece of the instrument and operated by the chin of the player. The muffling-lever is retained in a recess of the tail-piece by means of a spring when the muffling-plates are applied to the bridge, and released from the tail-piece by a downward pressure of the chin and returned into its normal position by a spiral spring located on one of the connecting-rods and interposed between a shoulder on the same and one of the guide-eyes on the tail-piece.

In the accompanying drawings, Figure 1 represents a top view of a violin with my improved muffling attachment. Figs. 2 and 3 are top views of the muffling attachment, drawn on a larger scale and shown, respect-

ively, in position before and while muffling. Figs. 4 and 4^a are vertical longitudinal sections on line x x and x' x', Fig. 2. Fig. 5 is a vertical transverse section on line y y, 55 Fig. 3; and Figs. 6 and 6^a are a detail end view and a vertical section of one of the muffling-plates.

Referring to the drawings, A represents the body of a violin or other stringed instrument; B, the tail-piece of the same, and C the bridge of the same. At opposite sides of the bridge C are arranged muffling-plates D D, which are preferably made of hard rubber or other suitable material. Each muffling-plate D is connected by a rod E with a muffling-lever F, which is fulcrumed to the under side of the tail-piece B, the connecting-rods E being pivoted to the levers F equidistantly from its fulcrum, as shown clearly in 70 Figs. 2 and 3. The muffling-plates D D are attached to the outer ends of the connecting-rods E, by providing the latter with shoulders d at a short distance from their ends and applying a washer d' to the opposite sides of the 75 plates and a screw-nut d^b to the threaded ends of the rods. In this manner the muffling-plates D are supported on the ends of the connecting-rods E E, but have a slight play on the same, so that the muffling-plates can be 80 applied with their entire surface from opposite sides to the bridge C when operated by the muffling-lever F. The muffling-plates D D are re-enforced at their outer surfaces by reinforcing plates of sheet metal. The muffling-plates can be readily removed and exchanged in case of the breaking of any one of them, the fastening devices facilitating the ready application of the plates to the rods. The connecting-rod of one of the muffling- 85 plates passes through one of the opening parts of the bridge without interfering with the same. The connecting-rods E E are guided in suitable eyes e e, which are attached to the under side of the tail-piece B, the openings of 90 said eyes being wide enough to permit the lateral play of the connecting-rods E in following the motion of the muffling-lever F. The muffling-lever F is so applied to its fulcrum that besides the oscillating motion on 95 the same parallel to the body of the violin it may also be vibrated up and down, so that

the lever can respond to the action of a spring *f*, that is attached to the under side of the tail-piece *B*, and applied by its free end to the under side of the longer arm of the muffling-lever *F*. The spring *f* exerts an upward pressure on the lever, so as to cause it to move into a recess *f'* at the under side of the tail-piece *B* whenever the lever *F* is moved forward by the action of the chin on the same. By this forward motion of the lever *F* the muffling-plates are applied to both sides of the bridge *C*, and thereby the sounds of the strings muffled or damped, as required, by the piece of music to be played by the player. One of the connecting-rods *E* is provided with a shoulder *g* and with a spiral spring *g'*, which is interposed between said shoulder and one of its guide-eyes *e*, as shown in Figs 2 and 3. The spring *g'* serves for the purpose of returning the muffling-lever and the muffling-plates to their former normal position whenever by the pressure of the chin on the top part of the muffling-lever *F* the same is released from the notch or recess *f'* of the tail-piece. The muffling-lever is guided by a keeper *f*², that is attached to the under side of the tail-piece *B*, as shown clearly in Fig. 4^a, which keeper limits the motion of the lever in horizontal as well as in vertical direction.

My improved muffling attachment to stringed instruments has the advantage that it can be operated with great facility by the chin of the player both in applying the muffling-plates to the bridge as well as in removing the same. It facilitates thereby the muffling of the sounds, as the mute attachment can be operated without interrupting the playing of the instrument and without any inconvenience to the player.

Having thus described my invention, I claim as new and desire to secure by Letters Patent—

1. The combination, with the bridge and tail-piece of a violin or other stringed instrument, of muffling-plates arranged at opposite sides of the bridge, and a chin-lever fulcrumed to the tail-piece and connected to the muffling-plates for applying the same to or removing them from the bridge, substantially as set forth.

2. The combination, with the bridge and tail-piece of a violin or other stringed instrument, of muffling-plates arranged at opposite sides of the bridge, a chin-lever fulcrumed to the under side of the tail-piece, and connecting-rods between the muffling-plate and the chin-lever, substantially as set forth.

3. The combination, in a violin or other stringed instrument, with the bridge and tail-piece of the same, of muffling-plates at opposite sides of the bridge, a chin-lever fulcrumed to the tail-piece, and connecting-rods applied to said muffling-plates and pivoted at opposite sides of the fulcrum of the chin-lever, substantially as set forth. 65

4. The combination, with the bridge and tail-piece of a violin or other stringed instrument, of muffling-plates arranged at opposite sides of the bridge, a chin-lever fulcrumed to the tail-piece, connecting-rods between the muffling-plates and the chin-lever, and means for locking the chin-lever to the tail-piece when the muffling-plates are applied to the bridge, substantially as set forth. 70

5. The combination, with the bridge and tail-piece of a violin or other stringed instrument, of muffling-plates arranged at opposite sides of the bridge, a chin-lever fulcrumed to the tail-piece, connecting-rods between the muffling-plates and the muffling-lever, eyes 80 on the tail-piece for guiding said connecting-rods, means for locking the chin-lever to said tail-piece, and means for returning the lever and muffling-plates into normal position on releasing the lever from the tail-piece, substantially as set forth. 85

6. The combination, with the bridge and tail-piece of a violin or other stringed instrument, of muffling-plates arranged at opposite sides of the bridge, a chin-lever fulcrumed 90 to the tail-piece, connecting-rods between the muffling-plates and chin-lever, a spring for lifting the chin-lever, and a notch or recess at the under side of the tail-piece for engaging the tail-piece, substantially as set forth. 95

7. The combination, with the bridge and tail-piece of a violin or other stringed instrument, of muffling-plates arranged at opposite sides of the bridge, a chin-lever fulcrumed to the tail-piece, connecting-rods between the 100 muffling-plates and chin-lever, a recess in the tail-piece for engaging the chin-lever, a spring for lifting the chin-lever, and a spring for returning the chin-lever into normal position, substantially as set forth. 105

In testimony that I claim the foregoing as my invention I have signed my name in presence of two subscribing witnesses.

WALTER THOMPSON.
